Primary Examiner — Jasmine Mlinarcik(74) Attorney, Agent, or Firm — Dickinson Wright PLLC; John S. Artz(57) CLAIM

The ornamental design for a hat, as shown and described.

DESCRIPTION

FIG. 1 is a front perspective view of the hat;

FIG. 2 is a front view of the hat;

FIG. 3 is a rear view of the hat;

FIG. 4 is a left side view of the hat;

FIG. 5 is a right side view of the hat;

FIG. 6 is a top view of the hat; and,

FIG. 7 is a bottom view of the hat.

The broken lines in the drawings illustrate portions of the hat that form no part of the claimed design.
